International Search Report and Written Opinion dated Jul. 14, 2020 in connection with International Patent Application No. PCT/CA2020/050552, 11 pages.

Primary Examiner — Elizabeth A. Albert

(74) *Attorney, Agent, or Firm* — Dorsey & Whitney LLP

(57) **CLAIM**

The ornamental design for a planter, as shown and described.

DESCRIPTION

FIG. 1 is an exploded top perspective view of a planter showing our new design;

FIG. 2 is an exploded bottom perspective view of FIG. 1;

FIG. 3 is an exploded front elevation view of FIG. 1;

FIG. 4 is an exploded rear elevation view of FIG. 1;

FIG. 5 is an exploded left side elevation view of FIG. 1;

FIG. 6 is an exploded right side elevation view of FIG. 1;

FIG. 7 is a top plan view of FIG. 1; and,

FIG. 8 is a bottom plan view of FIG. 1.

The broken lines illustrate environment that forms no part of the claimed design. The broken away symbols in the drawings indicate the appearance of any portion of the article between the break lines forms no part of the claimed design.

1 Claim, 6 Drawing Sheets
